Earl J. Bullard
By Cheever & Cox Atty's.

UNITED STATES PATENT OFFICE.

EARL J. BULLARD, OF MADISON, WISCONSIN.

COMPRESSION-SEAL FOR PISTONS.

1,388,168.

Specification of Letters Patent. Patented Aug. 23, 1921.

Application filed October 13, 1920. Serial No. 416,685.

To all whom it may concern:

Be it known that I, EARL J. BULLARD, a citizen of the United States, residing at Madison, in the county of Dane and State of Wisconsin, have invented a certain new and useful Improvement in Compression-Seals for Pistons, of which the following is a specification.

This invention relates to the cylinders of engines, pumps and the like in which a reciprocating piston is in use. The object of the invention is to provide a seal between the moving piston and the cylinder wall, which is effective at all temperatures to prevent the escape of compressed gas, air vapor or liquid confined by the piston within the cylinder, past the piston as it moves in one direction and which prevents the pumping of oil by the piston into the compression space of the cylinder.

The invention consists in a particular packing ring and the use of that ring with and without other ring combinations on the piston of a cylinder of the class described which attains the foregoing objects. More particularly it consists in a device easily and cheaply made, efficient and satisfactory in use and not liable to get out of order, and also in many features and details of construction hereafter more fully set forth in the specification and claims.

Referring to the drawings in which similar numerals indicate the same parts throughout the several views,

Figure 1 is a sectional view of the cylinder of an engine of the combustion type having a vertically reciprocatable piston, shown partially in section therein, the same equipped with the device of this invention in its two most important forms.

Fig. 2 is a perspective view of an ordinary piston ring equipped with one of the rings of this invention.

Fig. 3 is a perspective view of a plain ring of this invention.

Fig. 4 is a sectional plan view on the line 4-4 of Fig. 1.

Fig. 5 is a perspective view of a spring ring constituting part of the invention.

Fig. 6 is a side view of the two ends of the ring of Fig. 3 separated one from the other.

From the earliest history of the use of a cylinder and reciprocating piston as a pump or engine, packing rings have been used on the piston to prevent the passage of gas or

liquid more or less compressed, from one end of the piston to the other, the earliest type being a leather or felt washer which was good enough at atmospheric temperature and low pressure, but the development of the modern high speed, high pressure and high temperature engine of the automobile and air craft arts has created an imperative demand for a perfect compression seal between piston and cylinder which has not, prior to this invention, been met in a practical way, though thousands have shot at the mark.

The desired result is attained by taking any piston 10 adapted for reciprocation in a cylinder 12 and providing it, unless already equipped, as is apt to be the case with one or more circumferential ring grooves or seats 14 and 16 with an ordinary, relatively wide expansion ring 18, of conventional form without novelty, but of less width than the width of the seats 14 and combining with the foregoing the ring of this invention to make the seal of this invention.

In carrying out this invention the ring 20 is provided of suitable diameter to lie in ring seats 14 or 16 and contact the inner circumference of cylinder 12. The ring is preferably made about one thirty second of an inch thick. It is equipped with notched ends 22 and 24 overlapping on a circumferential cut 26 which permits circumferential expansion of the ring but prevents the passage of gas or the liquid radially in the plane of the body of the ring.

This ring may be of any suitable material having sufficient elasticity so that the ring will expand to the cylinder walls. Copper or brass may be used for the purpose.

This ring is placed on the side of the ring seat 14 or 16 occupied by ring 18 which is farthest away from the combustion chamber 28, of the cylinder 12. In the particular case here illustrated the engine is vertical with the combustion space at the top of the cylinder so the ring 20 is placed in each case below the ring 18. Where as shown in connection with the upper ring 18 in ring seat 14 of Fig. 1 no other parts are added the device works very well; the pressure of gas or liquid in space 28 above ring 18 engaging that ring and pressing down on ring 20 to make an effective seal.

However, the preferred construction is that shown in connection with the lower ring 110

18 in groove 16 of Fig. 1 in which the parts are exactly the same as before except that a supplemental spring ring 32 is interposed above ring 18 in the ring seat 16. In the 5 particular case here illustrated ring 32 is exactly like ring 28 except that it is laterally sprung (the drawing being very much exaggerated) sufficiently so that when put in place as shown, it acts as a spring to force 10 ring 18 down on ring 20.

It is important in assembling the parts to have the joints 34, 26, and 36 of the respective rings break joint with each other.

In the operation of the device the commercial ring 18 carries the load of scraping 15 along the inner circumference of the cylinder in the ordinary manner and more or less effectively seals at all points thereon except at the joint 34 but the ring 20 being pressed 20 at all points onto the side of ring seats 14 or 16 prevents the escape of compression between the ring 20 and the seat and being provided with the joint 26 prevents the passage of compressed gas or liquid in any 25 direction. In the preferred constructions the spring ring 32 enforces this action.

In applying the mechanism to worn engines which would ordinarily require new, expensive rings of the type of ring 18 all the 30 operator has to do is to take shavings off from the sides of rings seats 14 and 16 to make them wide enough to receive the rings 20 with or without the ring 32 and the reconstruction is complete.

Having thus described my invention what

I claim as new and desire to secure by Letters Patent, is:—

1. In mechanism of the class described, in combination with a piston having a circumferential ring seat of substantial width, a 40 ring of any suitable construction occupying most of the width of the ring seat and a relatively thin ring having a circumferential expansion joint, interposed between the wide ring and the ring seat wall and held in 45 place by the wider ring to make an effective compression seal, and a spring ring occupying the space between the other side of the wider ring and the ring seat.

2. In mechanism of the class described, in 50 combination with a piston having a circumferential ring seat of substantial width, a ring of any suitable construction occupying most of the width of the ring seat and a 55 relatively thin ring made of relatively soft metal having a circumferential expansion joint, interposed between the wide ring and the ring seat wall and held in place by the wider ring to make an effective compression seal, and a spring ring occupying the space 60 between the other side of the wider ring and the ring seat.

In witness whereof I have hereunto subscribed my name in the presence of two witnesses.

EARL J. BULLARD.
